CLAIM

The ornamental design for table for audio/visual equipment, as shown and described.

DESCRIPTION

FIG. 1 is a top, left isometric view of a table for audio/visual equipment showing our design.

FIG. 2 is a front elevational view thereof; the rear elevational view is a mirror image of FIG. 2.

FIG. 3 is a right-side elevational view thereof; the left-side view is a mirror image of FIG. 3.

FIG. 4 is a top plan view thereof; and,

FIG. 5 is a bottom plan view thereof.
